SAFETY PILOT BURNER

Theodore B. Focke, Cleveland Heights, and Allen K. Phelps, East Cleveland, Ohio, assignors to Perfection Stove Company, Cleveland, Ohio, a corporation of Ohio

Application October 20, 1939, Serial No. 300,438

5 Claims. (Cl. 158—115)

This invention relates, generally, to fluid fuel combustion apparatus, and it has to do particularly with a novel form of pilot burner for use with such apparatus and a safety control system involving the same.

To the end of safety, our invention has, as its primary object, to provide, in combination with one or more main fluid fuel burners, a unique fluid fuel pilot burner and a control system involving the same by which a supply of fuel to the main burner or burners is permitted only in case the pilot burner is functioning properly to light said main burner or burners.

Another object is to provide a convenient and reliable lighting means for the pilot burner; and, according to one form of the invention, to combine with such lighting means a control that acts to shut off the fuel supply to the pilot burner in case its flame accidentally becomes extinguished, and which serves to re-establish the fuel supply to the pilot burner upon subsequent actuation of the lighting means.

Further and more limited objects are: to provide, in conjunction with one or more main burners, a plural jet pilot burner including means for effectively communicating combustion from one jet to another; to combine therewith an igniter arranged in lighting relation to one of said jets, and a heat energized instrumentality that controls the supply of fuel to the main burner or burners and is arranged in heat receiving relation to another jet, and, still more limitedly, to provide, in association with a plurality of main burners, an elongated pilot burner possessing the foregoing features arranged with the igniter at one end, the heat energized instrumentality at the other, and the lighting jets for the main burners therebetween so as to insure against delivery of fuel to the main burners unless the pilot burner is properly functioning.

The foregoing objects and advantages, with others hereinafter appearing, including simplicity and economy of construction, facility of assembly and installation, reliability and durability are attained in the embodiments of the invention illustrated in the accompanying drawings wherein Fig. 1 is a plan view of our improved pilot burner showing it in operative relation to a plurality of main burners; Fig. 2 is a side elevation of what is shown in Fig. 1; Fig. 3 is a perspective view of the pilot burner assembly; Fig. 4 is a detail in the nature of a front elevation of the pilot burner body and cover with a part of the cover broken away; Fig. 5 is a section on the line 5—5 of Fig. 4 on a scale twice that of the latter view; Fig. 6

a diagrammatic representation of one form of the invention; and Fig. 7 is a similar view showing another form thereof.

While our invention is applicable to various kinds of combustion apparatus, we have selected as an illustration of a practical application its incorporation in the combustion apparatus of a gas fired furnace. Only such elements of the apparatus are included in the drawings as are essential to a proper disclosure of the invention, and in this connection it may be explained that the diagrams of Figs. 6 and 7 have been simplified by omitting therefrom all features ordinarily included in such control systems but which have no bearing on the instant invention.

The invention, in its broader aspect, is applicable to one or more main burners, or to a multiple main burner of two or more independent sections or units. According to the illustrative embodiments herein disclosed, there are three such burners or units, designated 1, 2 and 3. A mixture of primary air and gas is supplied to each burner or unit through an inducer 5 whose outer end incorporates the usual shutter-controlled air mixer 6 into which fluid fuel or gas is projected through a nipple 9 from a manifold 10. As shown in Fig. 2, each inducer 5, with a burner mounted thereon, is supported through legs 11 from a base 12. The pilot burner assembly, designated generally by the numeral 15, is supported from the base 12, in operative relation to the main burners, by standards 16 to the upper ends of which are connected, by bolts 18, brackets 20 and 21 that form parts of the assembly 15. Secured, as by welding or otherwise, within substantially semi-circular notches in the front edges of the brackets 20 and 21 is the cylindrical tubular body 25 of the pilot burner. The body is closed at its ends, and its front wall (that nearest the main burners) is provided at intervals therealong with jet apertures of appropriate size, designated 26, 27 and 28. Extending along the same wall of the burner body between said jet apertures are relatively small and comparatively closely spaced perforations 29 that provide the fuel to transmit combustion from one jet to another, this end being further served by an overhanging cover 30 that is substantially L-shaped in cross section and has the rear edge of its top wall welded or otherwise secured to the top of the burner body. The front wall of the cover is cut away at its ends, as indicated at 31, and intermediate its ends is provided with a notch 32, so as not to interfere with the lighting jets projected from the apertures 26, 27 and 28.

Diametrically across from the respective apertures 26 and 28, the rear wall of the pilot burner body 25 is provided with apertures 34 and 35, and transverse slots 36 and 37 are formed in the lower side of the body between the corresponding front and rear apertures. The inlet tube or inducer of the pilot burner is designated 39 and joins the body 25 toward one end thereof. The brackets 20 and 21 include laterally extending flanges or ledges 40 and 41, respectively, and supported by a mounting 43 from the ledge 40 is an electric igniter designated generally by the reference numeral 45.

The igniter consists of a body 48 of suitable insulating refractory material, and a resistor coil 47 disposed within a groove thereof. The ends of the coil are connected to screws 48 that extend through the body and have nuts applied to their ends, thereby to provide binding posts for the attachment of conductors. The parts are so arranged as to dispose the igniter in line with the aperture 34 so that a jet of fuel issuing therefrom will impinge against the resistance coil and be ignited thereby when said coil is energized. As will be readily understood, combustion from this igniting jet will be instantly transmitted through fuel escaping from the adjacent slot 36 to the jet of fuel projected from the aperture 26. The flame from the last mentioned jet is propagated along the line of perforations 29 beneath the cover 30 to the jets of fuel issuing from the apertures 27 and 28, from the latter of which combustion is transmitted by the fuel issuing from the slot 37 to that issuing from the aperture 35, the latter providing what may be termed the heating jet. Supported by the flange or ledge 41 of the bracket 21 is a heat energized instrumentality or thermosensitive element 50, the one illustrated being a thermocouple which has the capacity to generate electric current when heated. This element is arranged for impingement against it of the aforesaid heating jet.

Referring now to the diagram of Fig. 6, fluid fuel is supplied from a suitable source to the main burners 1, 2 and 3 through a pipe 55 that is connected to the manifold 10. Included in the gas supply line or pipe 55 is an automatic valve 56 that is biased toward closed position, as by gravity, and is adapted to be opened by electrical means, such as a solenoid 57. A pipe 58 is shown as leading from the pipe 55, in advance of the valve 56, to the pilot burner, and the supply pipe may be equipped with a manual valve 59 in advance of its connection with the pipe 58.

60 designates a transformer, the primary winding 60^a of which is in the house circuit that may be of the usual 110 volts and is represented by the conductors 61 and 62. The secondary winding 60^b of the transformer is placed in circuit with the igniter 45 through conductors 63 and 64, the latter including a push button switch 65. Through conductors 67 and 68, the thermocouple 50 is placed in circuit with the winding of a relay 70, whose armature 71 is normally held away from the core of the relay by a light spring 72. When energized, the relay moves the armature 71 into engagement with a contact 73. 75 represents a thermostatic switch or so-called room thermostat that is subjected to the heat output of the combustion apparatus or furnace.

According to the simplified control system herein disclosed for illustrative purposes, the room thermostat, under the influence of a temperature of given value for the maintenance of

which it is set, and with the main burners out of operation and only the pilot burner functioning, is in condition to maintain the circuit in which it is included open. Assuming that the manual valve 59 is adjusted to supply fuel to the apparatus, gas will issue from the several jet apertures of the pilot burner, the igniting jet impinging against the resistance coil of the igniter 45. To start the apparatus in operation, the push button switch 65 is closed thereby to establish a circuit through the secondary winding of the transformer, the conductor 63, igniter 45, and conductor 64. When the coil becomes sufficiently hot, it will ignite the gas issuing from the aperture 34, and combustion will be communicated therefrom across the slot 36 to the aperture 26 and along the row of perforations 29 to the apertures 27 and 28 and across the slot 37 to the aperture 35, the flame of the jet issuing from the latter aperture impinging against the thermocouple 50. When sufficiently heated, the thermocouple will generate current in the circuit represented by the conductors 67 and 68 and including the winding of the relay 70, thereby to energize the relay and attract the armature 71 so as to engage it with the contact 73. Assuming, now, that the temperature to which the room thermostat is subjected has fallen below the aforesaid given value, the movable contact member 76 of said thermostat will swing into engagement with the contact member 71, thereby to close the circuit including, besides the room thermostat, the secondary winding of the transformer, the solenoid 57, and the armature of the relay 70, said circuit being represented by the conductors 78, 79, 80 and 81.

It will be seen, therefore, that as long as the pilot burner is operating and heating the thermocouple 50, the relay 70 will function to maintain the circuit including the room thermostat and the solenoid 57 closed at the relay, thus placing the automatic valve 56 solely under the influence of the room thermostat to be opened when occasion requires.

The modification of the invention illustrated in Fig. 7 differs from that shown in Fig. 6 only by the inclusion of an automatic valve for controlling the supply of fuel to the pilot burner, and a thermocouple, in association with the igniter 45, with its relay and necessary circuits. Therefore, in the diagram of Fig. 7, all parts corresponding to those of the diagram of Fig. 6 will be designated by the same reference numerals. In the form of the invention shown in Fig. 7, a pipe 58^a that conducts gas from the supply pipe 55 to the pilot burner includes an automatic valve 85 that is biased toward closed position and is adapted to be opened by a solenoid 86. A thermocouple 88 is arranged in intimate heat exchanging relation to the igniter 45 and is desirably in the path of the jet of gas issuing from the aperture 34. Through conductors 89 and 90, the thermocouple 88 is placed in circuit with the winding of a relay 91 whose armature 92 is held away from the core of the relay by a light spring 93. When the relay is energized, the armature 92 will be attracted and swung into engagement with a contact member 94. The winding of the solenoid 86 and the armature of the relay 91 are placed in circuit with the secondary winding 60^b of the transformer through conductors 96, 97 and 98.

When the parts are cold, the supply of gas to the pilot burner will be shut off by the automatic valve 85. When it is desired to set the apparatus in operation, the push button switch

65 is closed thereby to energize the igniter 45. When the temperature of the igniter becomes sufficiently high to transmit enough heat to the thermocouple 88 to cause it to generate current, the relay 91 will be energized, thereby to swing the aperture 92 into engagement with the contact 94, establishing the circuit that includes the secondary winding of the transformer and the winding of the solenoid 86. Upon energization of the solenoid 86, the valve 85 will be opened to supply fuel to the pilot burner, and when the pilot burner is once in operation, the heat from the flame of the igniting jet will maintain the thermocouple 88 hot, thereby to supply current to the relay 91 and maintain closed the circuit including the solenoid 86 that acts, under such conditions, to hold the automatic valve 85 open. Should the flame of the pilot burner become accidentally extinguished, the thermocouple 88 will cool, thereby to deenergize the relay and open the circuit that includes the winding of the solenoid 86 and, as a consequence, allow the valve 85 to close.

Having thus described our invention, what we claim is:

1. A safety pilot burner comprising an elongated hollow body having jet apertures spaced therealong and rows of perforations between apertures, a stationary cover extending along the body and permanently overhanging said perforations and cut away adjacent each aperture to prevent interference with the jet projected therefrom, and means for admitting fluid fuel to the body.

2. A safety pilot burner comprising a hollow elongated body having a plurality of jet apertures in its front wall spaced apart longitudinally thereof, one of said apertures being adjacent each end of the body, said front wall being provided also with perforations in series between said apertures, a stationary cover extending along the body and permanently overhanging said perforations and cut away adjacent each aperture to prevent interference with the jet issuing therefrom, the rear wall of the body being provided with apertures substantially diametrically opposite those apertures of the front wall that are adjacent the ends of the body, the bottom wall of the body having openings between the apertures of the rear wall and the corresponding apertures of the front wall, and means for admitting fluid fuel to the body.

3. A safety pilot burner comprising a hollow elongated body having a plurality of jet apertures in its front wall spaced apart longitudinally thereof, one of said apertures being adjacent each end of the body, said front wall being provided also with rows of perforations between said ap-

tures, a stationary cover fixed with respect to the body and permanently overhanging the front wall thereof and having a part extending downwardly in opposed relation to said wall, said part being cut away opposite each aperture, the rear wall of the body being provided with apertures substantially diametrically opposite those apertures of the front wall that are adjacent the ends of the body, the bottom wall of the body having openings between the apertures of the rear wall and the corresponding apertures of the front wall, and means for admitting fluid fuel to the body.

4. A safety pilot burner comprising a hollow elongated body having a plurality of jet apertures in its front wall spaced apart longitudinally thereof, one of said apertures being adjacent each end of the body, said front wall having rows of perforations between said apertures, a stationary cover permanently overhanging the front portion of the body in opposed relation to the front wall thereof and cut away opposite each aperture, the rear wall of the body being provided with apertures substantially diametrically opposite those apertures of the front wall that are adjacent the ends of the body, the bottom wall of the body having openings between the corresponding apertures of the front and rear walls, supporting means secured to the body, one in the region of each of the apertures of the rear wall, and means for admitting fluid fuel to the body.

5. A safety pilot burner comprising a straight cylindrical tubular body closed at its ends, an inducer communicating with the body for admitting a fluid fuel mixture thereto, the front wall of the body being provided with jet apertures spaced apart longitudinally thereof, one of said apertures being located adjacent each end of the body, said front wall being provided also with perforations in series between said apertures, the rear wall of the body having jet apertures substantially diametrically opposite the apertures of the front wall that are adjacent the ends of the body while the bottom wall of the body has openings between the corresponding apertures of the front and rear walls, a cover fixedly attached to the top of the body and permanently overhanging the front side thereof and including a wall spaced from the front wall of the body in opposed relation thereto, said wall of the cover being cut away adjacent each aperture of the front wall of the body to prevent interference with a jet issuing therefrom, and brackets secured to the body adjacent the ends thereof, each bracket including a supporting part in the region of one of the apertures in the rear wall of the body.
